US0D1020682S

(12) **United States Design Patent** (10) **Patent No.:** **US D1,020,682 S**
(45) **Date of Patent:** **** Apr. 2, 2024**

(54) **SPEAKER**

(71) Applicant: **Anker Innovations Technology Co. Ltd.**, Changsha (CN)

(72) Inventor: **Zhengwen Liu**, Shenzhen (CN)

(73) Assignee: **Anker Innovations Technology Co. Ltd.**, Changsha (CN)

(**) Term: **15 Years**

(21) Appl. No.: **29/783,954**

(22) Filed: **May 17, 2021**

(30) **Foreign Application Priority Data**

Nov. 19, 2020 (CN) 202030700701.2

(51) **LOC (14) Cl.** **14-01**

(52) **U.S. Cl.**

CLAIM

The ornamental design for a speaker, as shown and described.

DESCRIPTION

FIG. 1 is a front perspective view of a speaker showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is an enlarged view of the encircled portion 7 indicated in FIG. 1.

The even-length broken lines depicting the small circular regions on the top surface of the speaker and the remainder of the speaker form no part of the claimed design. The

(Continued)

uneven-length broken lines in FIGS. 1 and 7 are used for demonstrating an enlargement and form no part of the claimed design.

1 Claim, 7 Drawing Sheets
